UNITED STATES PATENT OFFICE

JACOB S. KAMBORIAN, OF WATERTOWN, MASSACHUSETTS, ASSIGNEE TO NORTHERN MACHINE CO., INC., OF BOSTON, MASSACHUSETTS, A CORPORATION OF MASSACHUSETTS

SHOE BOTTOM TREATING DEVICE

Application filed September 26, 1930. Serial No. 484,553.

My present invention relates to devices for treating the bottoms of shoes, and is particularly applicable to McKay shoes, and more particularly to McKay shoes when made with cementing processes and without the use of tacks, although said device is also applicable to welt shoes.

When manufacturing shoes by a cementing process, where tacks are not used, and particularly at the toe portion, the shoe is placed in a bed lasting machine and the toe portions of the upper materials are wiped over by the lasting wipers. This operation is repeated a few times, but as soon as stopped, the upper materials have a tendency to assume their normal position before the cement has set. Also, the lasting wipers are not of themselves capable of exerting pressure in such a way as to level and smooth the upper materials at this point, with the result that when the outsole is applied, there will be lumps or ridges between the outsole and insole at the toe portion of the shoe, unless that portion of the shoe bottom is flattened by a separate operation after removed from the lasting machine. I am aware that it has been proposed to cement the edge of the upper to the insole and to hold it while the cement is set by devices having insole penetrating prongs, nails, or the like, but such devices so far as is known to me have never proven commercially successful since they do not furnish the requisite flattening pressure, they are difficult to remove; they tend to injure the shoe parts; and in some instances necessitate the use of special lasts.

My present invention is intended and adapted to eliminate and obviate the difficulties above mentioned, and in a preferred embodiment comprises means adapted to pull over and wipe the toe portions of the upper materials after they are first wiped by the shoe lasting wipers of a bed lasting machine.

Primarily the object of the invention is to provide means adjunctive to the bed lasting wipers which will exert sufficient pressure upon the upper materials at the forepart or toe of the shoe to smooth and

level the same so as to eliminate wrinkles, corrugations or the like while holding them in this position until the cement has set sufficiently to retain them permanently.

In a preferred embodiment of the invention, the apparatus is so devised as to effect a sliding action over the shoe bottom, from the toe toward the heel, and thereafter to exert a clamping action under desired pressure for a predetermined interval of time, until the cement has set. When the device is then removed from the shoe, the upper materials will be securely held in position by the cement, and all wrinkles, ridges or other objectionable protuberances will be smoothly ironed out.

My present novel device is adjustable for varying lengths of shoes, and is also adjustable to varying sizes of lasts.

The clamping plate utilized may be automatically adjustable to varying widths of toes, and if so adjustable may be spring controlled.

The above and other objects of the invention, details of construction, combinations of parts and advantages, will be hereinafter more fully pointed out, described and claimed.

Referring to the drawing, illustrating a preferred embodiment of the present invention,

Fig. 1 is a side elevation of my novel device in operative position;

Fig. 2 is a plan sectional view on the line 2-2 of Fig. 1;

Fig. 3 is a sectional view on the line 3-3 of Fig. 1;

Fig. 4 is a cross-sectional view on the line 4-4 of Fig. 1;

Fig. 5 is a bottom plan view of the pivoted clamping plate; and

Fig. 6 is a cross-sectional view on the line 6-6 of Fig. 5.

Referring now to the drawing for a particular description of one desirable embodiment of the invention, its construction and operation, my present novel device comprises a substantially L-shaped frame including an arm 1 having at one end thereof a cup-shaped member or cap 2 pivoted at 100

3 and adapted to fit over the peak 4 of the forepart of a last 5.

The other arm 6 of the frame has a longitudinal slot 7, said two arms being in the shape of an L. Cooperating with the arm 6 is a bracket 8 dovetailing with said arm for guidance, as clearly illustrated in Fig. 4. A bolt 9 extends through the bracket 8, having a squared portion 10 to prevent rotation, and having a threaded stem 11 extending through the arm 6. A wing nut 12 is provided to clamp the arm 3 and bracket 8 in adjusted position, a washer 13 being interposed between the wing nut 12 and arm 6.

The bracket 8 is angled to form an extension 14 having a threaded boss 15 at its outer end. Through this threaded boss is adapted to be screwed a threaded stem 16 having a handle 17 on its upper end and a rounded knob 18 on its lower end; said parts constituting reversible pressure applying means, the screw threaded stem 16 being advanced to apply pressure and retracted to relieve the pressure.

This rounded end 18 is adapted to seat in a recess of depression 19 in a rivet 20, this rivet 20 uniting two sections 21 which in this instance collectively form the clamping or leveling plate. This plate is devoid of prongs, nails, or other retaining elements (such as would penetrate the shoe parts, particularly the insole) for holding the plate in place, the plate being held in accordance with the present invention by clamping means independent of the plate, and when hereinafter I refer to the plate as having a "smooth" surface, it is to be understood that the surface thus referred to is devoid of attaching prongs or the like. However, if desired, and as shown at 22, I may knurl the surface of the plate to insure a gripping thereof on the edge of the upper material 24. Obviously, if desired, the stem 18 may be permanently united to the plate to maintain the stem and plate in operative relationship at all times.

The under surfaces of these sections 21 may be knurled or roughened as illustrated at 22, to insure a gripping thereof on the edges 23 of the upper materials 24. A spring 25 is provided, having a bearing in each of the sections 21 and normally tending to hold said parts in separated position.

The operation of my novel device is simple, and will be readily understood by those skilled in this art.

After the insole 26 and upper materials 24 have been assembled on the last 5, and while said last is in a lasting machine (not illustrated), the lasting wipers 27 are operated to pull over and wipe the edges 23 of the upper materials at the toe part.

The wipers 27 are then separated a sufficient distance to allow the application of the

plate 21 to the toe of the shoe bottom, as illustrated in dotted lines in Fig. 1. The cap 2 is then fitted over the peak of the last and the arm 1 swung until the knob 18 can be seated in the depression 19 in the rivet 20. Thereupon the parts will be in the position illustrated in dotted lines in Fig. 1.

Thereafter, on rotation of the handle 17, the stem 16 will be advanced downwardly through the boss 15, exerting pressure on the plate sections 21. This pressure will tend to move the stem 16 and hence the plate sections 21 toward the heel of the shoe, the clamping action being ceased when the sections 21 have reached a position approximately as illustrated in full lines in Fig. 1.

This clamping and moving action will not only complete the pulling over action, but will also smooth out, level and press the edges 23 of the upper materials at this toe portion.

As the sections of the plate 21 are moved toward the heel, they will expand and abut against the wipers 27, the spring 25 forcing said sections outwardly, so as to insure perfect action on the edges 23.

The device is left in clamping position for a predetermined length of time dependent upon the time of setting of the cement employed, and is then removed (the stem 16 having first been retracted), at which time the cement will have set and the upper materials will be securely held in permanent position, ready for the application of the outsole.

My novel clamping plate thus holds the shoe upper in final lasted position, firmly, smoothly and solidly, preferably bearing on the upper close to the edge of the insole to which it is lasted and over the edge of the last. Also, while I prefer to hold my clamping device by a separate clamp and pivoted arm, as shown, the clamping device can be held by any other means desired, the improved feature being that the toe portion of the shoe is thus completely lasted by adhesive, it being noted in particular that the pressure applying means embodies no parts or elements which must penetrate, perforate, pass through or otherwise injure or require modification of the insole of the shoe, automatically smoothing or ironing out wrinkles, ridges or the like, at the toe portion and eliminating toe tacks, wires, or other devices. The softening effect of the cement at the toe, particularly when the toe portion of the shoe is first heated in the usual toe stamping apparatus to soften the box and facilitate the pulling over, gives an effectual smoothing action and result to my toe clamp.

The adjustability of the bracket 8 on the arm 6 permits a single device to be utilized on a wide range of shoe sizes with equal facility, and the pivoting of the cup 2 per-

mits fitting the device to a wide range of last sizes.

My present device is simple, strong, economical and efficient, and its advantages and utility will be instantly appreciated by those skilled in the art. I believe that this device is novel, and have therefore claimed the same broadly in the present application.

While I have necessarily described my present invention somewhat in detail, it will be appreciated that I may vary the size, shape and arrangement of parts within reasonably wide limits without departing from the spirit of the invention.

It will also be appreciated that other clamping means may be utilized on the bracket 8 in place of the threaded stem if desired.

My invention is further described and defined in the form of claims as follows:

1. A device of the kind described, comprising a substantially L-shaped frame, a pivoted cup at the end of one arm of the frame, a bracket on the other arm of the frame, a threaded stem carried by said bracket, a plate adapted to bear against a shoe bottom, said plate comprising two pivoted sections, and means to clamp said threaded stem against said plate.

2. A device of the kind described, comprising a substantially L-shaped frame, a last-engaging cup at the end of one arm of the frame, a bracket on the other arm of the frame, a threaded stem carried by said bracket, a plate adapted to bear against a shoe bottom, said plate comprising two relatively movable sections, spring means to normally retain said sections in expanded position, and means to clamp said threaded stem against said plate.

3. A device of the kind described, comprising a substantially L-shaped frame, a pivoted cup on one end of one arm of the frame, a slidably adjustable bracket on the other arm of the frame, a threaded stem carried by said bracket, a plate adapted to bear against a shoe bottom, said plate comprising two relatively movable sections, spring means to normally retain said sections in expanded position, and means to clamp said threaded stem against said plate.

4. A device of the class described comprising a frame, last engaging means pivotally secured to the frame, an adjustable bracket carried by the frame, and means associated with the bracket for clamping the margin of the toe portion of a shoe upper against an insole mounted on the last, said clamping means comprising a threaded stem carried by the bracket and a plate of a shape and size substantially conforming to the contour of the toe portion of the shoe bottom, said plate being adapted to rest upon the margin of the upper, the plate and stem having en-

gaging parts such as to permit the plate to rock relatively to the stem.

5. Shoe lasting means for use in a lasting process in which the margin of the toe portion of the shoe upper is wiped in over the insole by means of lasting wipers, said lasting means comprising a presser shaped to conform substantially to the toe portion only of the insole, and reversible pressure applying means movable relatively to the pressure and operative by advancing movement to force the presser against the wiped-in margin of the upper of the toe only, with sufficient pressure to flatten and level the marginal material, said presser being freely removable from the insole upon reverse movement of the pressure applying means.

6. A shoe lasting means for use in a lasting process in which the edge of the fore-part of the upper is held in lasted position by means of cement, said means comprising a substantially rigid, unyielding plate adapted to overlie and to engage the folded-in portions of the upper at the toe portion only of the shoe, and reversible pressure applying means independent of the plate, operative by advance movement temporarily to hold said plate against the folded-in upper material with sufficient force to smooth and level said material and for a sufficient time to permit the retaining cement substantially to set, the plate being freely removable from the shoe bottom upon reverse movement of the pressure applying means.

7. Shoe lasting means for use in a lasting process in which the edge of the fore-part of the upper is held in lasted position by means of cement, said lasting means comprising a substantially rigid plate adjunctive to the wipers of a bed lasting machine, said plate conforming in shape and size substantially to the toe portion of the shoe bottom, and being devoid of insole penetrating elements, the plate being adapted to be disposed upon the folded-in edge of the upper after withdrawal of the lasting wipers from wiping position, and reversible pressure applying means operative by advance movement to force the plate against the folded-in material with pressure sufficient to level and flatten said material while holding it in such position until the retaining cement has set.

8. Shoe lasting means for use in a lasting process in which the margin of the fore-part of the upper is wiped in by the use of lasting wipers and is permanently retained in lasted position by means of cement, said means comprising a plate adapted to engage and temporarily to hold in wiped-in condition the margin of the toe portion of the shoe upper after withdrawal of the lasting wipers, and reversible pressure applying means movable relatively to the plate for forcing the latter with substantially un-

yielding pressure against the wiped-in margin of the upper whereby to flatten and level the marginal material and to hold it for a sufficient time to permit retaining cement to set.

9. Shoe lasting means for use with a last upon which are assembled the upper and insole of a shoe, with the margin of the upper wiped in over the insole, said lasting means comprising clamping means removably associable with the last and including a substantially rigid plate adapted to hold the wiped-in margin of the upper against the insole, and reversible pressure exerting means movable relatively to the last and operative to cause the plate to exert pressure localized upon the margin of the upper at the toe portion only of the shoe, the plate being freely removable from the shoe bottom when the pressure exerted by the pressure applying means is relieved.

10. Shoe lasting means for use with a last upon which are assembled the upper and insole of a shoe, with the margin of the upper turned down upon the insole, said lasting means comprising clamping means removably associable with the last and including a substantially rigid presser shaped to conform substantially to the contour of the toe portion only of the insole, and reversible pressure applying means movable relatively to the last for causing the presser to exert localized pressure upon the marginal portion of the upper at the toe of the shoe sufficient to flatten and level said marginal portion.

11. Shoe lasting means for use with a shoe last having assembled thereon a shoe upper and insole, with the margin of the upper at the toe at least folded in over the bottom surface of the insole, said lasting means comprising pressing and holding means engageable with the folded-in marginal toe material only of the upper to flatten and level said material at the toe portion only of the shoe, and reversible pressure applying means reacting directly between the last and said holding means for causing said holding means to exert flattening pressure upon said material.

12. Shoe bottom flattening means for use subsequent to the folding in of the edges of a shoe upper by the wipers of a bed lasting machine, said flattening means comprising last engaging means, a removable, substantially rigid and unyielding plate adapted to be placed in direct overlying contact with the folded-in portions of the upper material when the bed lasting wipers are retracted, and to exert localized pressure upon said material to keep the latter smooth and flat while retaining cement is setting, and means comprising relatively movable parts interposed between the last engaging means and the plate, and operative to press the

plate into flattening contact with the folded-in portion of the upper material.

13. Apparatus for use in lasting shoes in accordance with a process in which the edges of the upper are secured to the insole by means of adhesive, said apparatus comprising last engaging means, a device shaped to conform substantially to the contour of the toe portion only of a shoe bottom and to overlap the lasted-in margin of the upper, said device having a smooth under surface adapted to exert localized pressure on the lasted-in margin to make the latter flat and level, a stem projecting upwardly from said device for manipulating it, and means reacting between the last engaging means and the stem for holding said pressure applying device in contact with the lasted-in margin of the upper.

14. Means for clamping the margin of an end portion of an upper in lasted position upon an insole, comprising a clamping device portable with the shoe and having opposite side portions hinged together for relative adjustment laterally of the shoe.

15. A pressure applying device useful in bed-lasting shoes, said device comprising a substantially unyielding presser member conforming substantially to the contour of a portion at least of the forward part of the insole, said member being devoid of insole penetrating elements and having a substantially smooth under surface adapted to be placed in direct overlying contact with the wiped-in marginal portion of the upper material at the forepart of the shoe after the bed-lasting wipers have been retracted out of engagement with the wiped-in material, and reversible pressure applying means, devoid of insole penetrating elements operative to transmit pressure to said presser member while the latter is in contact with the wiped-in material at the forepart of the shoe, thereby to smooth and flatten said material and to hold it while retaining cement is setting, said presser member being freely removable from the shoe when the pressure is relieved.

16. A pressure applying device, useful in bed-lasting shoes, for transmitting flattening pressure to the marginal material of the shoe upper after the latter has been wiped-in over the insole by the bed-lasting wipers, said device comprising a pair of curved elongate substantially rigid members independent of the lasting wipers and hinged together adjacent to one end, thereby permitting their free ends to be separated more or less, said members having lower surfaces for contact with the wiped-in upper material, and pressure applying means for pressing said device forcibly against the wiped-in marginal upper material.

17. A pressure applying device for use in cement-lasting shoes in a bed-lasting ma-

chine, said device being movable relative to the bed-lasting wipers and comprising members each curved to conform substantially to the contour of a portion of the outer edge of an insole, each of said members being of a width at least sufficient to cover substantially the entire width of the marginal wiped-in portion of the upper with which

said member contacts, and means hinging said members together for relative adjustment widthwise of the insole, said members having under surfaces adapted to rest upon and to flatten the wiped-in marginal material.
